DRESS

Billi Rubin, New York, N. Y.

Application May 3, 1951, Serial No. 15,050

Term of patent 14 years

(Cl. D3—26)

To all whom it may concern:

Be it known that I, Billi Rubin, a citizen of the United States residing at New York, in the county of New York, and State of New York, have invented a new, original, and ornamental Design for Dress, of which the following is a specification, reference being had to the accompanying drawing, forming part thereof.

Fig. 1 is a front elevational view of a dress showing my new design;

Fig. 2 is an inside view of the front half of the dress shown in Fig. 1 with the detachable panel in place, and

Fig. 3 is a view similar to Fig. 2 with the detachable panel removed.

The back of the dress is shaped like the front and is otherwise plain and unornamented.

I claim:

The ornamental design for a dress, as shown and described.

BILLI RUBIN.
